(57) **CLAIM**

The ornamental design for a headlamp, as shown and described.

DESCRIPTION

FIG. 1 is a perspective view of a headlamp according to my new design;

FIG. 2 is a front elevation view thereof;

FIG. 3 is a back elevation view thereof;

FIG. 4 is a top side elevation view thereof;

FIG. 5 is a bottom plan elevation view thereof;

FIG. 6 is a right side elevation view thereof;

FIG. 7 is a left side view thereof;

FIG. 8 is another perspective view thereof in an open configuration; and,

FIG. 9 is a right side elevation view thereof in the open configuration.

The broken line showing represents unclaimed portions of the article only and forms no part of the claimed design.

1 Claim, 9 Drawing Sheets
